STAMP AFFIXING MACHINE

Tomitaro Sano, Fowler, Calif.

Application September 29, 1948, Serial No. 51,707

8 Claims. (Cl. 216—25)

1

The present invention relates to new and useful improvements in stamp affixing machines and more particularly to a hand operated machine.

An important object of the invention is to provide a plunger operated carriage on which a roll of stamps is supported together with mechanisms for feeding the stamps in a step by step movement to a cutter which is synchronized with the feeding of the stamps and providing a moistening roller mounted for swinging movement under the carriage to fold the stamps under a presser plate and simultaneously moisten the underside of the stamps as the carriage is moved downwardly into its stamp affixing position.

A further object of the invention is to provide a stamp affixing machine of this character of simple and practical construction, which is efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a side elevational view;

Figure 2 is a view in elevation showing one of the open sides of the frame;

Figure 3 is a similar view of an opposite side of the frame;

Figure 4 is a vertical sectional view taken substantially on a line 4—4 of Figure 3;

Figure 5 is a similar view showing the completion of the downward stamp affixing movement of the carriage;

Figure 6 is a fragmentary vertical sectional view taken substantially on a line 6—6 of Figure 2;

Figure 7 is a transverse sectional view taken on a line 7—7 of Figure 4 and showing the cutter;

Figure 8 is a vertical sectional view taken on a line 8—8 of Figure 2, and

Figure 9 is an enlarged fragmentary vertical sectional view taken on a line 9—9 of Figure 2 and showing the guide channel for the cutter actuating slide.

Referring now to the drawings in detail wherein for the purpose of illustration I have disclosed a preferred embodiment of the invention the numeral 5 designates an inverted U-shaped stationary frame having an opening 6 in its top in which a plunger 7 is positioned for vertical reciprocating movement. The upper end of the

2

plunger is provided with a knob or handle 8 and an expandable coil spring 9 is positioned on the plunger between the top of the frame 5 and the knob 8 to move the plunger upwardly.

- 5 A carriage designated generally at 10 is secured to the lower end of plunger 7, the carriage being of open frame construction open at its opposite sides, the open sides of the carriage coinciding with the open sides of the frame 5.
- 10 A substantially hook shaped support or seat 11 is suitably secured to the underside of the top of carriage 10 and constructed of strap metal to form a seat for a roll of stamps 12 which is loosely supported on the seat or support 11 and with the free end of the roll extending downwardly under a feed roller 13 against which the stamp strip is held by a pressure roller 14 pivotally supported by the carriage 10 and provided with a spring 15 for holding the pressure roller against feed roller 13. The stamp strip is fed from the rollers 13 and 14 under a stationary guide plate 16 to the front edge of a horizontal reciprocating cutter designated generally at 17.
- 15 A gear 18 is rotatably mounted on one side of the carriage 10 engaging a gear 19 secured to one end of the shaft 20 for the feed roller 13. A ratchet 21 is secured to one side of gear 18 engaged by a row of teeth 22 on one edge of a vertical dog 23 which is pivoted as at 24 at its upper end to one side of the frame 5. The teeth 22 of the dog 23 are held in engagement with the ratchet 21 by means of a leaf spring 25 positioned longitudinally at the rear edge of the dog with its upper end secured to the stationary pivot 24 for the dog.
- 20 The teeth of the ratchet 21 and dog 23 are arranged to ride past each other during downward movement of the carriage 10 without rotating gear 18 and the return or upward movement of the carriage will cause a rotation of ratchet 21 by the teeth of the stationary dog 23 to thus rotate gear 18 and gear 19 and rotate feed roller 13 to feed the stamps in a step by step movement. The gear 18 is held against rotation during downward movement of the carriage by means of a dog 26 pivoted to one side of the carriage and engaging the teeth of gear 18.
- 25 Figure 11 includes a V-shaped blade 27 sliding horizontally in a guide 28 suitably carried at the lower end of carriage 10. An arm 29 is pivoted to the rear portion of blade 27 and is inclined upwardly therefrom and pivoted at its upper end to an arm 30 secured in a horizontal position at the lower end of a shaft 31 rockably mounted in a vertical sleeve or housing 32 secured

to one side of the carriage 10. The upper end of shaft 31 projects horizontally through an opening 33 in the adjacent side of carriage 10 to provide a slide 34 positioned for vertical sliding movement in a guide channel 35 secured to the adjacent inner side wall of the frame 5. The lower end of guide channel 35 is inclined as shown at 36 in a direction to rock shaft 31 and swing arm 30 in a forward direction to move blade 27 forwardly and to sever the stamp from the end of the stamp strip as the carriage 10 approaches its lowermost position.

A moistening roller 37 is journalled at the outer ends of a pair of arms 38 which are pivoted at their inner ends to the opposite ends of shaft 20 for feed roller 13. The arms 38 are positioned outwardly of the sides of the carriage 10 to swing vertically by means of a gear 39 secured to one of the arms 38 engaging a vertical rack bar 40 secured in a stationary position to the frame 5 by means of a bracket 41.

The vertical movement of carriage 10 swings arms 38 and moistening roller 37 downwardly under a curved presser plate 42 at the underside of cutter guide 28. As the moistening roller 37 moves downwardly during downward movement of carriage 10 the moistening roller engages the endmost stamp of the stamp strip and folds the same under the presser plate 42 and at the same time moistens the adhesively coated underside of the stamp and holds the stamp against the bottom of presser plate 42 during the severing action by cutter blade 27. The moistening roller 37 swings rearwardly past presser plate 42 as the stamp is pressed upon an envelope or the like, the presser plate 42 being of resilient material and free at one end to flatten itself upon the stamp by pressure exerted on the carriage by the plunger 7 and knob 8. During this action moistening roller 37 is swung upwardly against the underside of a shield or stop 43 at the rear edge of frame 5.

During raising movement of carriage 10 the moistening roller 37 is swung forwardly at the front of the frame 5 into engagement with an absorbent pad 44 held in a holder 45 suitably secured to the front edge of the frame 5, and saturated with a suitable liquid to be supplied to roller 37.

In view of the foregoing description taken in conjunction with the accompanying drawings it is believed that a clear understanding of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention, what is claimed as new is:

1. A stamp affixing machine comprising a stationary frame, a carriage slidable vertically in the frame and manually reciprocated, a stamp holder supported by the carriage for loosely holding a roll of stamps, a horizontally reciprocating cutter carried at the bottom of the carriage, mechanism feeding the stamps in a step by step movement to the front edge of the cutter, a moistening roller, means rockably supporting the roller on the carriage for oscillating movement under the cutter to simultaneously moisten the stamps and fold the same under the cutter, and operating

means for the roller connected to the carriage for operation by the movement of the carriage.

2. A stamp affixing machine comprising a stationary frame, a carriage slidable vertically in the frame and manually reciprocated, a stamp holder supported by the carriage for loosely holding a roll of stamps, a horizontally reciprocating cutter carried at the bottom of the carriage, mechanism feeding the stamps in a step by step movement to the front edge of the cutter, a moistening roller, means swingably supporting the roller on the carriage for oscillating movement under the cutter to simultaneously moisten the stamps and fold the same under the cutter, and rack and pinion operating means for the roller operated by the movement of the carriage.

3. A stamp affixing machine comprising a stationary frame, a carriage slidable vertically in the frame and manually reciprocated, a stamp holder supported by the carriage for loosely holding a roll of stamps, a horizontally reciprocating cutter carried at the bottom of the carriage, mechanism feeding the stamps in a step by step movement to the front edge of the cutter, a resilient presser plate at the underside of the cutter a moistening roller, means swingably supporting the roller on the carriage for oscillating movement under the cutter to simultaneously moisten the stamps and fold the same under the cutter, and rack and pinion operating means for the roller operated by the movement of the carriage.

4. The combination of a stationary frame and a vertically reciprocating carriage for a stamp affixing machine, of a horizontal reciprocating cutter at the bottom of the carriage, and mechanism for actuating the cutter and comprising a vertical rockably mounted shaft carried by the carriage, a slide at the upper end of the shaft, means connecting the lower end of the shaft to the cutter, a guide for the slide carried by the frame and shaped to cause a rocking movement of the shaft during vertical movement of the carriage, mechanism carried by the carriage for feeding stamps in a step by step movement to the cutter, a stamp moistening and folding roller carried by and actuated by the movement of the carriage for folding stamps under the cutter, and a resilient presser plate carried by the cutter holding the folded stamps against an envelope during the cutting action.

5. A stamp affixing machine comprising a stationary frame, a manually operated carriage reciprocably carried for vertical movement by the frame, a horizontally reciprocating cutter at the lower end of the carriage and operated by the movement thereof, a stamp strip feed mechanism carried by the carriage for feeding stamps in a step by step movement to the cutter, a swingably supported roller carried by the carriage for folding the stamps under the cutter, and operating means for the feed mechanism and for the roller and comprising a stationary pawl, a ratchet carried by the carriage and engaging the pawl during movement of the carriage, gearing connecting the ratchet to the feed mechanism, and a rack and pinion device connecting the swingably supported roller to the feed mechanism.

6. A stamp affixing machine comprising a stationary frame, a manually operated carriage reciprocably carried for vertical movement by the frame, a horizontally reciprocating cutter at the lower end of the carriage and operated by the movement thereof, a stamp strip feed mechanism carried by the carriage and operated by the movement thereof for feeding stamps in a step

by step movement to the cutter, a moistening roller swingably carried by the carriage for movement under the stamps to fold the stamps under the cutter, and operating means for the roller connected to the feed mechanism.

7. A stamp affixing machine comprising a stationary frame, a manually operated carriage reciprocably carried for vertical movement by the frame, a horizontally reciprocating cutter at the lower end of the carriage and operated by the movement thereof, a stamp strip feed mechanism carried by the carriage and operated by the movement thereof for feeding stamps in a step by step movement to the cutter, a moistening roller mounted on the carriage for movement under the cutter to simultaneously moisten and fold the stamps prior to severance thereof, and operating means for the roller connected to the feed mechanism.

8. A stamp affixing machine comprising a stationary frame, a manually operated carriage reciprocably carried for vertical movement by the frame, a horizontally reciprocating cutter at the lower end of the carriage and operated by the movement thereof, a stamp strip feed mechanism carried by the carriage and operated by the

10

15

20

25

movement thereof for feeding stamps in a step by step movement to the cutter, a moistening roller swingably carried by the carriage for movement forwardly and backwardly under the cutter to simultaneously moisten and fold the stamps under the cutter prior to severance thereof, and operating means for the roller connected to the feed mechanism.
